UNITED STATES PATENT OFFICE.

JAMES L. DE VOU, OF WISSAHICKON, PENNSYLVANIA.

DERRICK.

SPECIFICATION forming part of Letters Patent No. 739,955, dated September 29, 1903.

Application filed April 22, 1903. Serial No. 153,809. (No model.)

To all whom it may concern:

Be it known that I, JAMES L. DE VOU, a resident of Wissahickon, in the county of Philadelphia and State of Pennsylvania, have invented certain Improvements in Derricks, of which the following is a specification.

This invention relates particularly to traveling derricks or cranes for handling heavy loads. Its primary object is to provide improved means for automatically counterbalancing the load by which the weight of the load regulates the action of the counterbalance.

Further objects of the improvements are to attain flexibility and simplicity of construction and operation, to provide for the ready assemblage and dissociation of the parts, and to permit the ready movement and adjustment of the mechanism to the position of the load.

The nature and characteristic features of the improvements will more fully appear by reference to the following description and the accompanying drawings in illustration thereof, of which—

Figure 1 represents a side elevation of a derrick embodying the improvements. Fig. 2 represents a plan view of the same. Fig. 3 represents a sectional view taken on the line 3 3 of Fig. 1. Fig. 4 represents a perspective detail view showing the swivel mechanism for supporting the base of the boom. Fig. 5 represents a perspective view of part of the shoe for holding the swivel mechanism for the boom. Fig. 6 represents a perspective detail view showing mechanism for moving the counterbalance proportionately to the load. Fig. 7 represents a perspective view of the counterbalancing mechanism, and Fig. 8 represents a side elevation of a modified form of the construction.

As shown in the drawings, the car-frame 1 is provided with the rollers 2, upon which the derrick-base 3 is supported and moved, the frame having the flanges 1^a, which are engaged by the flanges 3^a of the base. The base 3 supports the mast 4, which comprises the struts 4^a, connected together by the compression members 4^b and the tension members 4^c, the truss thus formed being connected with the pedestals 5 by the hinges 6, which permit the mast to be broken and folded down. The mast holds at its top a bearing-

yoke 7, which is secured to the struts 4^a by the pivotal bearings 7^d. The yoke carries the bearing-block 7^a, having the pivotal bearings 7^b, and the tie-rods 8, connected to the outer end of the boom 9, pass freely through the holes 7^c of this block. Between the bearing-block 7^a and the bearing-plate 10, fixed to the inner ends of the tie-rods 8, are placed the coiled springs 11, which take up the stress upon the rods, these springs being compressed proportionately to the stress in the rods, which move in proportion to the load carried by the boom. Pivots connected with these rods in any suitable manner, as by an arm 12, fixed to the plate 10, is a rocking lever 13, which is carried by the arbor or shaft 14, supported by the bearings 14^a, carried by the mast. This lever carries the rack 13^a, which engages and turns a pinion 15^a, fixed on a shaft 15, which is journaled in bearings 16 in the pedestals. Fixed on the revoluble shaft 15 are the spools 17, about which are wound belts 18, connected with the counterweight 19 and passing over the pulleys 20. The weight 19 has the rollers 19^a, adapted to run on the rails 21, which are carried by the trussed beam 22, the beam having the pivotal connection 23 with the pedestal and the block-and-tackle connection 24 with the top of the mast. The boom 9 is provided with a universal movement by having its base pivoted to the swivel-block 25 through the pintles 25^a and having the block 25 connected by the pintles 25^b with the shoe 26 26^a, carried by the pedestal. By this means and the joint 9^a formed in the boom the latter is capable of being folded together and down, and by slackening off the mechanism 24 the mast may also be folded down, the several parts thus being readily folded and brought down upon the car for shipment. The load is lifted by the movable block 27 and the cable 28, the latter being fixed to the outer end of the boom and passed over the block 27 and the pulley 29 to the drum 30, which is revolved by the driving-rod 31 of the engine 32. When the load is thus hoisted, its component acting through the tie-rods 8 upon the springs 11 compresses these springs in proportion to the load, and the movement is multiplied and communicated to the counterpoise 19 to move it to the position on the

beam 22 required for balancing the load, the movement of the counterpoise being effected by means of the intermediate mechanism, comprising the lever 13, the shaft 15, and the 5 belts 18, operated by the movement of the tie-rods.

In the modified construction (shown in Fig. 8) the mast 4' is connected to the pedestal 5' by the hinges 6' and by the tie-rod 8' to the 10 boom 9'. The boom 9' has its swivel-block 25' connected with a movable bearing or piston 34, adapted to move in the way or cylinder 35, formed in or carried by the pedestal, the cylinder containing a medium, as the 15 coiled spring 37, opposing an increasing resistance to the inward movement of the piston, the spring being supported by the block or cylinder-head 38. A beam 39, having its inner end connected to the pedestal and its 20 outer end supported by a tie-rod 40, secured to the mast 4', carries the counterweight 42, which is connected to and moved by the piston 34. The movement of the counterweight to the position upon the beam required for 25 balancing the load may be effected by communicating the movement of the piston, through the rack 43, connected therewith, to the pinion 44, which drives the spool 45. A belt 46 is wound on this spool, passed over 30 the pulley 47, carried by the beam and connected to the lug 48 of the counterweight. The block 34 to render its movement free is carried by the rollers 49, journaled in the 35 pedestal.

Having described my invention, I claim—

1. In a derrick or crane, a mast, a boom connected to said mast, a counter-beam connected to said mast, a counterweight movable on said beam, mechanism for supporting and 40 permitting the movement of said boom proportionately to the weight supported thereby, a rack connected with and operated by the movement of said boom, a pinion connected with and operated by said rack, and mechanism connecting said pinion with said counterweight whereby said counterweight is moved, substantially as specified.
2. In a derrick or crane, mechanism for supporting the load, said mechanism comprising 45 a spring adapted to be moved in proportion to the load, a lever connected to and movable with said spring, an adjustable counterbalance for the load, and mechanism connecting said lever with and adjusting the position of said counterbalance, substantially as specified.

3. In a derrick or crane, a hinged mast, a pivotally-supported boom, mechanism for tying said boom to said mast, a counter-beam, mechanism for tying said counter-beam to said mast, a counterbalance movable on said beam, and automatic mechanism for adjusting the position of said counterbalance, substantially as specified. 60

4. In a derrick or crane, a mast, a boom having a swiveled support providing universal movement therefor, mechanism for tying said boom to said mast, a swiveled connection between said tying mechanism and mast, and an adjustable counterbalancing mechanism connected with said mast, substantially as specified. 65 70

5. In a derrick or crane, a mast, a pivoted bearing carried thereby, a pivotally-supported boom, a tension member and a spring connecting said boom and pivoted bearing, an adjustable counterbalance and mechanism operated by the stress in said tension member for adjusting said counterbalance, substantially as specified. 75 80

6. In a derrick or crane, a counter-beam, a counterweight movable on said beam, a movable belt connected with and moving said counterweight, a mast connected with said beam, a boom connected with said mast, and mechanism actuated by the load carried by 85 said boom for operating said belt and weight, substantially as specified.

7. In a derrick or crane, a car having ways thereon, a mast carried by and movable on said ways, a boom connected with said mast, and a counterbalance connected with said mast, substantially as specified. 90

8. In a derrick or crane, a car having ways thereon, a folding mast connected with said ways and rolling upon said car, a sectional boom connected with said mast, a beam carried by said mast, and a counterweight movable on said beam, substantially as specified. 95

9. In a derrick or crane, a car having longitudinal ways thereon, and hoisting mechanism carried by and movable on said ways, said hoisting mechanism comprising a boom and an adjustable counterbalance, substantially as specified. 100 105

In testimony whereof I have hereunto set my hand, this 18th day of April, A. D. 1903, in the presence of the subscribing witnesses.

JAMES L. DE VOU.
